UNITED STATES PATENT OFFICE.

JOHN S. FINCH, OF BRIDGEPORT, CONNECTICUT, ASSIGNOR TO THE SINGER MANUFACTURING COMPANY, A CORPORATION OF NEW JERSEY.

BUTTON-ATTACHING MACHINE.

1,364,265.

Specification of Letters Patent.

Patented Jan. 4, 1921.

Application filed September 9, 1918. Serial No. 253,136.

To all whom it may concern:

Be it known that I, JOHN S. FINCH, a citizen of the United States, residing at Bridgeport, in the county of Fairfield and State of Connecticut, have invented certain new and useful Improvements in Button-Attaching Machines, of which the following is a specification, reference being had therein to the accompanying drawings.

10 This invention relates to improvements in button attaching machines and particularly to improvements in the button-stapling machine disclosed in my pending U. S. application Serial No. 207,675, filed December 18, 15 1917, although the invention is equally applicable to other types of button attaching machines.

In machines of the class adapted to attach shank buttons to articles, the buttons 20 are usually guided to the attaching devices by means of an inclined chute and are placed in the chute by means of a feed-wheel positioned in a button-hopper or -receptacle. Difficulties have arisen in feed-wheels of 25 prior constructions in that frequently the shanks of the buttons were caught and pinched between the rigidly projecting teeth of the feed-wheel and the edge of the button-chute, thereby jamming the machine. 30 The same undesirable result was also frequently caused by the jamming of the buttons in the hopper between adjacent teeth of the feed-wheel.

The primary object of the present invention is to provide an improved feed-wheel 35 for button attaching machines obviating the defects inherent in feeding wheels of prior constructions.

The invention has for another object to 40 provide improved and convenient means for at will suspending the operation of the button-feed wheel without interference with the operation of the staple-forming and setting mechanism of the machine.

45 Other objects of the invention will be apparent from the following description and claims.

In accordance with the present improvement and in its preferred embodiment the 50 feed-wheel is carried by a feed-wheel actuating shaft passing through the button-hopper. The feed-wheel is formed with spaced projections or teeth of peculiar design and adapted to deposit the buttons 55 upon a slotted button-chute formed within

the hopper. The teeth of the feed-wheel are rhomb-shaped in cross-section and positioned with relation to the button-chute so as to initially present an obtuse angle of the rhomboid closely adjacent thereto. The 60 produced edge of the vertex of this obtuse angle is the cast-off edge for the buttons and a line coinciding with this edge would pass substantially in advance of the center of the feed-wheel. Consequently the angle 65 formed between the cast-off edge of a tooth and the adjacent edge of the chute is at all times less acute than when said cast-off edge, when produced, passes substantially through the center of the feed-wheel. The resulting 70 action is such that the shank of a button not correctly dropped in the slot of the chute is again diverted into the hopper instead of being pinched between a tooth of the feed-wheel and the side of the chute. 75

The bases of the feed-wheel teeth are inclined downwardly toward the chute to deflect the buttons upon the latter, and are inclined downwardly in a direction opposite to the direction of rotation of the feed-wheel so that the rear side of each tooth is shorter than the advance side of the succeeding tooth. By means of this construction, as the teeth plunge into the buttons in the hopper there is provided sufficient clearance to obviate jamming of the buttons in the space between two teeth and the hopper. 85

The feed-wheel is carried by a feed-shaft 90 suitably journaled in a button-hopper having a hinged cover. The hinged cover is operatively connected with devices whereby the lifting of the cover brings said devices into operation to render the feed-shaft actuating mechanism non-effective. 95

In the accompanying drawings, Figure 1 is a left side elevation of a portion of the button stapling machine embodying the present improvement with the button-hopper in closed position. Fig. 2 is a top plan 100 of a portion of the machine and showing the cover of the hopper in raised position. Fig. 3 is an elevation of the feed-wheel as viewed from the side opposite to that shown in dotted lines in Fig. 1. Figs. 4 and 5 are detail views of the disk provided for suspending the operation of the feed-wheel. 105

Referring to the drawings, the machine frame 1 is provided with standards 2, 3, which may be secured in the usual manner 110.

upon a supporting base (not shown). Suitably secured upon the machine frame 1 is the button-feeding frame 4, provided with the forwardly inclined button-chute 5 and the button-chute cover-plate 6 and carrying a button-hopper or -receptacle 7 provided with a hinged cover-plate 8. Journaled in suitable bearings formed in the button-hopper is a feed-shaft 9 upon which is secured 10 a feed-wheel 10 adapted to turn clock-wise when viewed as in Fig. 1 of the drawings.

To impart to the feed-wheel 10 the desired step-by-step rotary movements, there is suitably secured on the feed-shaft 9 a ratchet-wheel 11 adapted to be engaged by two spring-depressed pawls 12 and 13 pivoted respectively on disks 14 and 15, loosely mounted on said shaft. The disks 14 and 15 are connected by means of links 16 and 17, 20 with a cam-disk 18 and operate in a manner to turn the ratchet-wheel in a single direction during each of the oppositely directed movements of the cam-disk 18. The cam-disk 18 is carried by the main rock-shaft 19, 25 journaled in bearings provided in the frame 1 and to which is secured a triangular-shaped rock-lever 20 housed in the machine frame and suitably connected with a treadle-actuated rod 21.

30 Means are provided to suspend the feeding action of the feed-wheel without disturbing the operation of the fastening or attaching mechanism. To this end, a double disk 22 provided with peripheries of different radii is loosely carried by the shaft 9 and connected by means of a link 23 with the hinged cover-plate 8 in such a manner that movement of the cover-plate will oscillate the disk 22. The pawls 12 and 13 respectively carry pins 24 and 25 adapted to track the peripheries of the disk. When the cover-plate 8 is closed, the pins 24 and 25 track the peripheries having the smaller radii, thereby permitting the pawls to engage the ratchet-wheel 11 and actuate the feed-wheel. When, however, the cover-plate 8 is lifted, the disk 22 is turned to deflect the pawls out of operative engagement with the ratchet-wheel, thereby suspending 50 the operation of the feed-wheel.

Housed within the button-hopper and positioned closely adjacent the feed-wheel is an inclined button-chute 26, provided with an open slot 27 for the button-shanks and 55 communicating with the button-chute 5. The chutes 5 and 26 serve to deliver the buttons to the attaching mechanism by gravity action.

The feed-wheel 10 is provided with a plurality of non-radial teeth or projections 28 substantially rhomb-shaped in cross-section. The button cast-off edges 29 of the feed-wheel are the advance edges closest adjacent to the button-chute 26 and each of these 65 edges determine the vertex of an obtuse

angle of a rhomboidal tooth. A line coinciding with an edge 29 passes substantially in advance of the center of the feed-wheel and consequently the angle formed between an edge 29 and the adjacent edge of the 70 button-chute 26 is at all times less acute than when said cast-off edge, when produced, passed substantially through the center of the feed-wheel. The resulting action is such that the shank of a button not correctly dropped in the slot of the chute is pushed by said edge back into the hopper instead of being pinched between the tooth and the side of the chute.

The bases 30 of the feed-wheel teeth are 80 inclined in transverse directions, that is, downwardly toward the button-chute 26 to deflect the buttons upon the latter and also downwardly in a direction opposite to the direction of rotation of the feed-wheel. 85 The function of the latter inclination is to form the rear side 31 of each tooth shorter than the advance side 32 of the succeeding tooth. By means of this construction the button clearance between two teeth increases from the side 31 to the side 32, and therefore as the teeth plunge into the buttons in the hopper the additional clearance provided obviates jamming of the buttons in the space between two teeth and the hopper. 90 The inclined sides 31 and 32 of the teeth therefore act to properly pick up the buttons and deliver them upon the chute 26 in the desired manner.

Having thus set forth the nature of the 100 invention, what I claim herein is:—

1. In a button-attaching machine, a feed-wheel having a plurality of spaced teeth providing an increasing button clearance from the rear surface of a tooth to the advance surface of the succeeding tooth.

2. In a button-attaching machine, a rotary feed-wheel provided with a plurality of rhomb-shaped teeth having button-engaging surfaces inclined to the direction of 110 rotation of the feed-wheel and in which the rear button-engaging surface of each tooth is shorter than the advance surface of the succeeding tooth.

3. In a button-attaching machine, a feed-wheel having a plurality of spaced teeth of which the bases are inclined to provide an increasing button-clearance from the rear surface of each tooth to the advanced surface of its succeeding tooth and inclined in 120 the direction transverse to the button-clearance incline to discharge the buttons therefrom.

4. A rotary feed-wheel for button attaching machines, comprising a plurality of 125 spaced teeth each of which has substantially parallel button-engaging faces of which the advance face is of greater length than the rear face.

5. In a button-attaching machine, the 130

combination with a button-receptacle, a button-carrier housed within said button-receptacle, and means for actuating said button-carrier, of a movable cover-plate for said receptacle, and means for suspending the action of said button-carrier independently of said button-receptacle by movement of said cover-plate.

6. In a button-attaching machine, the combination with a button-receptacle, a button-carrier housed within said receptacle, an oscillating actuating shaft, and operative

connections between said actuating shaft, and said button-carrier whereby said button-carrier is driven in a continuous direction during each of the oppositely directed movements of said actuating shaft, of means for rendering said operative connections ineffective independently of said button-receptacle.

15 20
In testimony whereof I have signed my name to this specification.

JOHN S. FINCH.
